(57) **CLAIM**

The ornamental design for a double-sided puzzle as shown and described.

DESCRIPTION

FIG. 1 is a front elevationnal view of a double-sided puzzle showing my new design;

FIG. 2 is a front elevationnal view of a base plate of the double-sided puzzle shown separately for ease of illustration;

FIG. 3 is a front elevationnal view of front puzzle pieces of the double-sided puzzle shown separately for ease of illustration;

FIG. 4 is a rear elevationnal view of the double-sided puzzle; FIG. 5 is a rear elevationnal view of the base plate of the double-sided puzzle shown separately for ease of illustration; and,

FIG. 6 is a rear elevationnal view of rear puzzle pieces of the double-sided puzzle shown separately for ease of illustration.

The double-sided puzzle is substantially flat and the undisclosed thickness and the depth form no part of the claimed design.
